MATCH BOOK

Charles C. Baldwin, St. Louis, Mo.

Application June 22, 1938, Serial No. 215,250

2 Claims. (Cl. 206—29)

This invention relates to match books and has for its object to provide a comparatively simple and inexpensive device of this character, the match splints of which are pivotally mounted and normally housed within a protective cover or casing and adapted to be swung laterally to exposed position at the side of the casing to permit the match splints to be selectively detached and ignited without danger of burning the fingers or liability of premature ignition of the match splints or the breaking of the said match splints in the lighting process.

A further object of the invention is to provide a match book, the match striking surface of which is concealed within a cover assuring complete protection against moisture and dirt and also enhancing the appearance of the book and permitting additional space for advertising matter; said striking surface being incorporated upon one or more of the opposed inner faces of the cover so that by inserting the head of a match splint within the casing at said striking surface and exerting a slight inward pressure on the walls of the casing while at the same time withdrawing the match therefrom, ignition of said match will be quickly and safely effected.

A further object of the invention is to make the cover or casing of the match book from a single sheet or blank of paper or other suitable material so constructed that, when folded into shape, one side of the match book will provide an igniting channel adapted to operatively receive the heads of the match splints when lighting the same.

A further object is to normally expose one corner of the base end of the match splint card or insert at a corner of the cover or casing to provide a convenient fingerpiece whereby to facilitate swinging said match splint insert on its pivotal axis to exposed position when it is desired to detach a match.

A still further object of this invention is to provide a match book that can be easily opened and closed with one hand and generally to improve this class of devices so as to increase their utility, durability and efficiency.

In the accompanying drawings forming a part of this specification and in which similar numerals of reference indicate corresponding parts in all the figures of the drawings:

Figure 1 is a perspective view of a preferred form of a match book embodying the present invention showing the match splints swung laterally to exposed position to permit the detachment of a match.

Figure 2 is a similar view showing match splint cards housed within the casing and a match introduced within the igniting channel of the casing preparatory to lighting said match, the match splint insert being pivoted on leg of staple,

Figure 3 is a transverse front end view of Figure 1 showing the splints in closed position.

Figure 4 is a plan view of the blank from which the casing or cover is formed,

Figure 5 is a side elevation, partly in section, illustrating a modified form of the invention;

Figure 6 is a similar view showing another form of the invention;

Figure 7 is a perspective view illustrating a still further modification showing the match splints housed within the casing and a match introduced within the match igniting chamber of the casing preparatory to lighting said match,

Figure 8 is a vertical sectional view of the cover or casing as shown in Figure 7, and constructed from the blank as shown in Figure 10, with a further modified form of match splint card or insert being shown;

Figure 9 is a transverse front or top end view with splint cards in closed position as shown in Figure 8, and

Figure 10 is a plan view of the blank from which the modified cover or casing shown in Figures 7 and 8 is constructed.

The improved match book forming the subject-matter of the present invention comprises a protective cover or casing 4 preferably formed of a single sheet or blank of paper or other suitable material of the construction shown in Figure 4 of the drawings. The blank is provided with spaced intermediate fold lines 7 defining the bottom 8 of the match book and side walls 9 and 10 so that, when the blank is folded, a protective cover or casing will be provided consisting of the front and rear walls 9 and 10, and bottom wall 8. That end or top of the protective cover or casing opposite the bottom wall 8 is open and, pivotally mounted on an eyelet 11 or leg of staple as indicated at 11a or similar device between the front and rear walls of the cover at the top thereof, is a match splint insert, indicated at 12. The match splint insert 12 is normally housed within the protective cover or casing 4 and is adapted to be swung laterally on the pivot 11 to exposed position at the side of the cover when it is desired to detach any one of the individual match splints, as best shown in Figure 1 of the drawings. By constructing the blank in this manner when the latter is folded and assembled, an igniting channel 13 will be formed at one

side of the cover, said channel having an open end through the top thereof assuring easy insertion of a match. One or more of the inner opposed faces of the front and rear walls 9 and 10 is provided with a suitable match igniting compound 14 so that, when the head of a match is inserted within the channel 13 and a slight inward pressure exerted on the front and rear walls of the cover, the fulminate will be ignited as the match splint is withdrawn from the channel 13, as best shown in Figure 2 of the drawings. In order to facilitate moving the group of match splints to open and closed position, one corner of each wall 9 and 10 of the cover is cut away or so shaped at 15 so as to normally expose the adjacent corner of the match splint insert and permit said insert to be swung laterally at the side of the cover by merely pressing laterally on the exposed corner 16, as will be readily understood.

Under normal conditions, the match splint inserts are housed and protected within the cover or casing 4 so that the match book may be carried in the pocket in the usual manner. When it is desired to ignite a match, it is merely necessary to exert a slight lateral pressure on the exposed corner 16 of the match splint insert which will cause said match splint insert to swing laterally on its pivot 11 to extended position and in which position one of the match splints may be detached or severed from the group of splints and the head thereof inserted within the channel 13. By now exerting a slight inward pressure on the opposite walls of the cover 4 and simultaneously withdrawing the match from the channel, the head of the match will come in frictional contact with the striking surface 14 and ignite the match. Normally it is preferable to return the match splints to closed position before the match can be introduced within the channel 13, giving further protection against accidental ignition of the remaining match splints. It will be noted that the match striking surface 14 is entirely concealed within the cover thus insuring complete protection against dirt and moisture, while also further enhancing the appearance thereof and at the same time affording additional space on the front and rear of the cover for placement of suitable advertising matter when desired.

In Figure 5 of the drawings, there is illustrated a modified form of the invention in which the match splint card or insert is cut-away or so shaped at the base at 17 as to permit the insertion of a match splint head laterally between the front and rear portions of the cover or casing and in contact with the igniting surface 18 for lighting, and said splint card providing a finger or thumb engaging lug 19 extending laterally from the other side of the splint card or insert for convenience in swinging same laterally into open and closed positions.

In Figures 6 of the drawings, illustrating another modified form of the invention the match splint card or insert is the same as those shown in Figures 1 and 2 except that the base end of the splint card or insert is provided with a vertical lug 20 projecting beyond the end or top of the cover and adapted to be pressed laterally with the finger or thumb in order to swing the match insert to exposed position at the side of the cover.

In Figure 7 of the drawings, there is illustrated a still further modified form of the invention in which the protective cover or casing 21 prefer-

ably formed of a single sheet or blank of paper or other suitable material of the construction shown in Figure 10 of the drawings, and consisting of an elongated body portion 22 provided intermediate its length with spaced transverse fold lines 23 defining front and rear walls 24 and 25 and an integral bottom wall 26. One of the walls 24 and 25 of the blank, preferably the back wall 25, is provided with a lateral extension or flap 27 and a longitudinal fold line 28, the free end of the flap being inclined in the direction of the body of the blank, as indicated at 29, in order to economize material and lessen the weight of the match book. The flap or extension 27 is provided with a fold line 30 disposed at an angle to the longitudinal fold line 28 so that, when the blank is folded, a protective cover or casing will be provided consisting of the front and rear walls 24 and 25, bottom wall 26 and a tapered side wall 31. That side of the cover opposite the tapered wall 31 is open and pivotally mounted on an eyelet or similar device between the front and rear walls of the cover at the open top thereof is a match splint insert, indicated at 32 in Figures 8 and 9 of the drawings. Match striking surface 33 as shown best in Figure 10 of the drawings is formed on one or more of the opposed inner faces of the walls to effect ignition of the head of a match splint when the latter is inserted between the cover sections 25 and 27 and a slight inward pressure exerted thereon as the match is withdrawn from the cover, as shown in Figure 7 of the drawings. In this form of the device the cover is cut-away or so shaped at 34 to expose a corner 35 of the match splint insert to facilitate moving the match splints to open position as previously described.

In Figure 8 of the drawings, there is illustrated a vertical sectional view of the cover or casing as shown in Figure 7, and showing a modified form of the device, a match splint card or insert 32 which being provided with a laterally extended lug 36 completely incloses the igniting channel when the match splints are in closed position, giving complete protection against dirt and dampness, as best shown in Figure 9 of the drawings.

It will be noted that in all forms of the device the match splint insert is pivotally mounted within a protective cover or casing and is movable laterally to exposed position at the side of the cover and that in each instance the match striking surface is entirely concealed so as to prevent moisture from coming into contact with said match striking surface and preventing proper ignition of the matches.

It will, of course, be understood that the match books may be made in different sizes and shapes and the protective covers thereof constructed of paper, aluminum or any other suitable material without departing from the spirit of the invention.

Having thus described the invention, what is claimed as new is:

1. A blank for match book covers, formed of a single sheet of material and comprising an elongated body portion having spaced intermediate transverse fold lines and a longitudinal fold line defining the said elongated body portion, and provided at one end thereof with an integral lateral extension or flap, said extension being provided with a fold line disposed at an angle to the adjacent longitudinal fold line, and inclined in the direction of one end of said blank, the extension and adjacent portion of the body of

the blank being provided with a match-striking surface adapted to be concealed within the cover when the blank is folded into shape.

2. A match book embodying a match splint insert and a one-piece cover overlapping the insert on opposite faces thereof and extending beyond the side edges thereof at one side and forming overlying margins, said margins having match striking material on the inner faces

thereof adjacent the base of the insert, and a relatively wide staple having one leg thereof passed medially through the ends of the cover and enclosed insert to form a pivot and its other leg passed through the said overlying margins of the cover adjacent one edge of the insert and near the zone of the match striking material.

CHARLES C. BALDWIN.
